CLAIM

The ornamental design for an aircraft as shown and described.

DESCRIPTION

FIG. 1 is a front perspective view of an aircraft showing our new design;

FIG. 2 is a rear perspective view thereof;

FIG. 3 is a front view thereof;

FIG. 4 is a rear view thereof;

FIG. 5 is a side view thereof;

FIG. 6 is a side view opposite that of FIG. 5;

FIG. 7 is a top view thereof; and,

FIG. 8 is a bottom view thereof.

The dash-dash broken lines shown in the drawings illustrate portions of the aircraft that form no part of the claimed design. The dash-dot broken lines shown in the drawings define the bounds of the claimed design and form no part thereof.

FIG. 1

FIG. 3

FIG. 4

FIG. 5

FIG. 6

FIG. 8
